ULIN S. ANDERSON, DECEASED, LATE OF DALLAS, TEXAS, BY LOU BELLE ANDERSON,
ADMINISTRATRIX, OF DALLAS, TEXAS.

FUSE-BLOCK.

1,113,528.

Specification of Letters Patent.

Patented Oct. 13, 1914.

Application filed September 8, 1913. Serial No. 788,515.

To all whom it may concern:

Be it known that ULIN S. ANDERSON, deceased, late a citizen of the United States, residing at Dallas, in the county of Dallas 5 and State of Texas, did invent certain new and useful Improvements in Fuse-Blocks, and I, LOU BELLE ANDERSON, administratrix, a citizen of the United States, resident of Dallas, in the county of Dallas and State of

10 Texas, do hereby declare that the following is a specification thereof.

The invention relates to a new and useful fuse block, and is particularly intended for use in a primary circuit.

15 The fuses of a primary circuit are most frequently burned out at night, when the circuit is most heavily loaded. The breaking down of the fuses is most commonly due to the wires of the circuit becoming excessively charged by lightning during a rain 20 storm. Thus the work of installing new fuses to replace those that have burned out must usually be done at night and during a down pour of rain, under which disadvantageous conditions, the workman will incur a considerable risk of being electrocuted, unless the fuse blocks are so constructed 25 as to eliminate this risk.

The primary circuit fuse blocks that are 30 commonly used in the present practice, are so constructed to receive wire fuses, the extremities of which must be secured to the circuit terminals by binding screws, requiring the use of a screw driver. This 35 construction is objectionable for the reason that an electrician working at night is handicapped by the necessity of using a screw driver and is often occasioned much trouble and loss of time to the binding 40 screws being accidentally dropped to the ground from the top of the pole. A further objection to the type of fuse-blocks that are commonly used in primary circuits lies in the fact that a workman engaged in installing 45 new fuses must place his hands in dangerously close proximity to the wires of the circuit. Another objectionable feature of the common fuse block is that an arc may be formed between the terminals of the fuse 50 block, when the workman has removed the plugs from the block to place new fuses upon the plug.

It is one object of the invention to provide a fuse block adapted to receive fuses 55 of the cartridge type, so constructed that

they may be expeditiously installed without the use of tools.

Another object of the invention is to provide a fuse block having a fuse-carrying cap disposed at its extremity opposite to that 60 at which the circuit wires enter the box, so that a workman may remove the cap without placing his hands in proximity to the wires.

A further object of the invention is to provide a fuse block having a fuse-carrying cap, so formed as to provide ample insulation between the fuses and the hands of a workman grasping the cap.

Still another object is to provide a fuse 70 block to be interposed in one side of a primary circuit and containing two fuses, so that any arc that may be formed between the terminals of one fuse after said fuse has burned out will be destroyed by the 75 burning out of the other fuse.

Finally, the object of the invention is to provide a device of the character described that will be strong, durable, simple and efficient, and comparatively easy to construct. 80

With these and various other objects in view, the invention has relation to certain novel features of the construction and use, an example of which is described in the following specification, and is illustrated in 85 the accompanying drawing, wherein:

Figure 1 is a front view of the improved fuse block, showing a portion of the bracket upon which the block is mounted. Fig. 2 is a top view of the fuse block with its cap 90 removed. Fig. 3 is a bottom view of the cap. Fig. 4 is a view of the fuse block in vertical sectional elevation, the section being taken through the center lines of the two fuses. Fig. 5 is a detail sectional view, 95 the section being taken upon the line Y—Y of Fig. 4. Fig. 6 is a detail vertical sectional view of the same, the section being taken upon the line Z—Z of Fig. 5.

Referring now more particularly to the 100 drawing, wherein like reference characters designate similar parts in all the figures, the numeral 1 denotes the body of the fuse block, which will preferably be formed of porcelain. Upon the rear face of the body 105 1, there is integrally formed a rectangular projection 2, by which the said body is held slightly spaced from the metal bracket 3 to which the body 1 is secured by the bolts 4. In the body 1, there are formed two 110

vertical tubular fuse receiving apertures 5 opening in the top of said body and terminating in its lower portion. With the bottom of each aperture 5, there communicates a tubular aperture 6 of decreased diameter, opening in the bottom of body 1. In each aperture 6, there is inserted a binding post 7, formed at its upper end with an annular flange 8 adapted to rest upon the bottom of the aperture 5. Upon the flange 8 of each post 7, there is formed a number of depending pins 9, which, when said posts have been inserted into the apertures 6, will enter suitable sockets formed in the bottom 15 of the apertures 5. The wires 10 comprising one side of the primary circuit are introduced into the body 1 from opposite sides of said body through horizontal apertures 10^a communicating with the apertures 6, and 20 are engaged in a permanent contact with the binding posts 7 by binding screws 11. In order to securely hold the binding posts 7 to their proper place at all times, a small quantity of sealing wax is poured into the 25 apertures 5 upon the flanged upper portions of said post. In order that the flanged upper ends of the binding posts may be securely embedded in the sealing wax, a recess 12^a is formed at the bottom of each 30 aperture 5, serving to conduct the sealing wax beneath the flange 8.

The body is adapted to receive upon its upper extremity a porcelain cap 13, formed in its under face with an aperture 14 adapted 35 to snugly receive the upper end of the body 1. A large knob 15 will be formed on top of the cap to serve as a handle by which the cap may be gripped. Within the aperture 14 at one side thereof, there is formed 40 integral with the cap 13 a rectangular block 15^a, which, when the cap is mounted in its proper position upon the body 1, will enter a suitable aperture 16 formed in the top of said body. In the aperture 14, there is, 45 furthermore, centrally mounted an electrical conductor having the nature of a metal plate 16^a, contiguous with the under surface of the cap 13, and formed upon one edge with a pair of lugs 17 which are bent 50 at right angles to the plate and are bolted to the block 15^a. The plate 16^a forms a support for and establishes electrical connection between two fuses 18 of the cartridge type, which fuses are each provided at one 55 extremity with a metal cap 18^a carrying a stud bolt 19 adapted to be engaged in a suitable threaded aperture provided in said plate. The cap 13 may be formed with recesses 20, adjacent to the apertures receiving the stud bolts 19, said bolts being permitted to project into said recesses. The other extremity of each fuse 18 is provided with a metal cap 21 which is gradually tapered to a point. The fuses 18 are so 65 spaced and proportioned that they may be

inserted into the apertures 5 as the cap 13 is being mounted upon the body 1. When the cap is mounted upon the body, the tapered caps 21 of the fuses 18 will be engaged within sockets 22, one of which is 70 mounted upon each post 7. Each socket 22 comprises a plurality of resilient metal strips forming substantially a tube, said strips being spread slightly from the center of said socket when the cap 21 is inserted 75 in the correlated socket.

In order that the air within the apertures 5 may have an outlet, when suddenly expanded, due to the heat generated by the burning out of a fuse, the apertures 5 are 80 made to communicate at their lower extremities with passages 23 communicating with an opening 24 in the bottom of the member 1.

When a fuse block embodying the above 85 described novel features is installed in a primary circuit, the current, under normal conditions will flow between the two wires 10, through the binding posts 7, the fuses 18, and the metal plate 16^a. When either 90 fuse 18 is burned out, there will be no flow of current through the fuse block, unless an arc is formed between the caps carried by the extremities of the burned out fuse. If, however, such an arc is formed, 95 the other fuse 18 will be immediately burned out, preventing any possibility of further arcing. Owing to the considerable space lying between the cap 13 and the wires 10, an electrician may remove or 100 replace said caps without bringing his hands in close proximity to the wires. It is to be furthermore observed that the cap 13 absolutely prevents any moisture from finding its way into the fuse block. It will be 105 readily seen that the fuses 18 may be mounted upon the cap 13 or removed from said cap without necessitating the use of any tools.

The invention is presented as including 110 all such changes and modifications as properly come within the scope of the following claims.

What is claimed is:

1. In a fuse block, an insulating body having parallel elongated recesses, binding posts, one mounted in the body at the bottom of each recess, sockets mounted on the ends of the binding posts within the recesses of the body, an insulating cap fitting 115 on the body, a contact plate secured in the cap, and a pair of fuses removably attached to the plate and positioned so as to project into the recesses of the body, and engage in the sockets.

2. In a fuse block, an insulating body having a pair of parallel elongated recesses and a central wall between the recesses, binding posts mounted in the body at the bottom of the recesses, spring sockets mounted on the 120

binding posts within the recesses, an insulating cap fitting on the body, a contact plate secured in the cap, fuses removably mounted on the plate and depending into the recesses of the body, said fuses having reduced ends entering the sockets, and means for fastening the block in an upright position.

3. A fuse block comprising an insulating body formed with two tubular apertures communicating with its top, a pair of binding posts mounted in said body at the lower end of said aperture, a cap superimposed upon the body, a socket superimposed upon each binding post within the correlated aperture, and means for mounting a pair of fuses upon the cap such as to establish a connection between the same.

4. A fuse block comprising an insulating body formed with two tubular apertures communicating with the top of the body, which apertures have communication with vent passages opening at the bottom of the body, a cap superimposed upon the body, and means for mounting upon the cap fuses

received by said tubular apertures of the body.

5. A fuse block comprising an insulating body formed with two parallel tubular apertures opening in the top of the body, vent 30 passages establishing communication between said tubular passages and the exterior face of the body, binding posts disposed adjacent to the bottom of each tubular passage, a socket surmounted upon each 35 binding post, a cap separably surmounted upon said body, a metal plate mounted upon the under face of the cap, fuses being mounted in the tubular apertures of the body establishing electrical connection be- 40 tween said sockets and said metal plate.

In testimony whereof I have signed my name to this specification in the presence of two subscribing witnesses.
